UNITED STATES PATENT OFFICE.

WILLIAM J. CONWAY, OF SAN FRANCISCO, CALIFORNIA.

TRUCK-LOADING DEVICE.

1,393,345.

Specification of Letters Patent. Patented Oct. 11, 1921.

Application filed August 27, 1920. Serial No. 406,350.

To all whom it may concern:

Be it known that I, WILLIAM J. CONWAY, a citizen of the United States, and a resident of the city and county of San Francisco, 5 State of California, have invented a new and useful invention—to wit, Improvements in Truck-Loading Devices, of which the following is a specification.

My invention has for its object means for 10 simplifying the loading of trucks and the like, and is particularly adapted to loading modern auto trucks with or without a dumping body and with the least expenditure of labor.

15 Other objects will appear from the drawings and description which follow.

Figure 1 is a side elevation of a truck equipped with my loading device.

Fig. 2 is a rear elevation of Fig. 1.

20 Fig. 3 is a detail of portions of my loading device.

Throughout the figures similar numerals refer to identical parts.

The frame of the truck is shown by the 25 numeral 1 carried upon suitable springs 2—2 and mounted upon the wheels as 3, 4 and 5. Mounted upon the chassis is the body 6 adapted to convey loads. In trucks heretofore it has been difficult to lift the 30 loads in place from the street level 7, and I therefore mount upon the body the pivoted members 8—9, pivoted as at 10—11 to the body 6 or if preferred it may be pivoted to the frame 1. These members normally 35 occupy a substantially vertical position, and are each connected as by the side strap 12 with a horizontal member 13 also pivoted at 10, and which with the vertical members 8—9 form two bell cranks operable about 40 the pivots 10, 11, into any position as shown, for example by the dotted lines 14—15.

Bridging the two members 8—9 I mount a 45 horizontal truss 16 which may be adjusted to any desired position on 8, 9, as by the strap bolts 17—18 and which will swing from the full line position of Fig. 1 into the dotted line position by movement of and with the members 8 and 9. To the outer end of the member 13 I attach a cable 18 passing 50 around the pulley 19 and thence around the winding drum 20 which latter is rotated by the gear 21, pinion 22 and crank arm and handle 23, so that said cable may be wound or unwound as desired, drawing down the 55 member from 15 into the position 13, and co-

incident therewith the member 8 from position 14 into position 8. Similar action occurs at the same time on the opposite side of the truck to move the member 9 as by the winding of the cable 24 on the drum 25. It 60 will be seen that the drums 20 and 25 are rigidly mounted upon the shaft 26 and are operable by winding the handle 23; also the members 8—9 may be turned backward as far as desired during which the truss 16 will 65 descend over any desired load, see Figs. 1 and 3, as upon the ground 7 when the tackle 27 may be employed to engage the said load, and thereafter the two cables 18 may be re-wound on the drums 20 and 25 on each side 70 of the truck by the operation of the handle 23, thus drawing down the two members from their dotted position as 15 to the full line positions as 13, and at the same time raising the load which now will swing with 75 the truss 16 on to the floor 28 of the truck body. The device may also be used if desired for unloading by reversing the above operation.

I prefer to form the strut or bars 12 with 80 bolts at 29, 30, such that they may be readily removed and the members 8—9 hinged downward as in the direction of the arrow 31 when they will lie directly adjacent to the horizontal members as 13, thus collapsing 85 the loading device into a minimum of space when out of operation.

The operation is as follows: The handle 23 is rotated to unwind the cables 18—24, and the members 8, 9 of the truss 16 are 90 pulled backward until such time as the sling or other tackle 27 is sufficiently low to allow the load to be lifted. The load is now made fast to the tackle 27 and the cables 18 and 24 are wound up on the drums 20 and 25, 95 during which the load will travel from its position as shown at 32 in the direction of the arrow 33 until it has arrived upon the truck at 28. It will be seen that this can 100 readily be accomplished by one operator even when the load is of considerable weight or bulk as compared with two or more men necessary without my loading device.

By locating the pivots 10, 11 on the body 105 of a truck which body is in turn pivoted to the frame of said truck, the body may be used to dump the load in the well known way in which case it is raised as through the arc 34 without disturbing the loading device.

I claim:

1. In a loading device for trucks and the like, a vertically disposed lever pivoted at its lower end on each side of said truck, a truss between said levers, a horizontally disposed member on each side and carried by the aforesaid pivots and connected as a bell crank with the corresponding lever, operating means for said members whereby the levers are rotated about their pivots through an angular movement whereby a load suspended from said truss may be raised or

lowered, wherein the truss is vertically adjustable to various positions on the levers.

2. Apparatus as set forth in claim 1,¹⁵ wherein the connection between each lever and member may be disconnected permitting the lever to be folded down adjacent the member thus collapsing the device when out of use.

In testimony whereof, I have hereunto set my hand at San Francisco, California, this 13th day of August, 1920.

WILLIAM J. CONWAY.
